UNITED STATES PATENT OFFICE.

CHARLEY S. MOOK AND BERNARD H. JANSEN, OF CLEVELAND, OHIO.

STOP AND WASTE COCK.

SPECIFICATION forming part of Letters Patent No. 781,784, dated February 7, 1905.

Application filed August 27, 1904. Serial No. 222,409.

To all whom it may concern:

Be it known that we, CHARLEY S. MOOK and BERNARD H. JANSEN, citizens of the United States, residing at Cleveland, in the county of 5 Cuyahoga and State of Ohio, have invented certain new and useful Improvements in Stop and Waste Cocks; and we do declare that the following is a full, clear, and exact description of the invention, which will enable others 10 skilled in the art to which it appertains to make and use the same.

Our invention relates to stop and waste cocks; and the invention comprises means to confine the plug within the body of the cock 15 and to change the direction of rotation of the plug to provide either a right or a left stop and waste cock, all substantially as shown and described, and particularly pointed out in the claim.

20 In the accompanying drawings, Figure 1 is a side elevation of our improved stop and waste cock and partly sectioned to disclose the construction and relation of parts. Fig. 2 is a plan view in horizontal section on line 25 $x-x$, Fig. 1, and Fig. 3 is a horizontal section on line $y-y$, Fig. 1, with the stops arranged to provide a waste from the left. Fig. 4 is a perspective view of the screw - confining cap for the plug. Fig. 5 is a perspective view of the neck portion of the coupling-body, and Fig. 30 6 is a perspective view of cap-inclosing band. Fig. 7 is a perspective view of the plug alone.

A represents the coupling-body with the valve or plug B set therein and adapted to 35 operate as usual without being set, as required. Plug B also has the usual passage 2 and waste-passage 3, and a corresponding waste-hole 4 is provided in body A. These are common features in all devices of this kind, 40 but are incident to and coöperate with the novel features of our invention.

Body A in our device has a threaded neck which is provided with lugs 5 and 6, extending 45 upwardly from its upper edge and arranged substantially ninety degrees apart. Plug B is tapering and rests in the tapering seat of the body and has its lower portion flush with the face of the lower portion A' of the body. Plug B is provided at its upper end with an 50 integral flange or collar b, which flange or col-

lar is above and removed from lugs 5 and 6. An extension B' of plug B projects above said collar, and a square opening is provided centrally within the plug through said extension for the removable handle C.

55 A screw-cap D is threaded to engage the threaded neck a and has an inturned flange d snugly fitting around extension B' and bearing down upon collar b to hold plug B to its seat within body A. Said cap also serves as a sand-cap to prevent dirt from entering said valve-seat. To make the valve-plug reversible, so that the waste-opening can be brought to either right or left sides, we provide a screw-stop 8, which is adapted to be screwed within 60 either of the two openings 9 or 10. Cap D has a slot or opening d' in its side which comes opposite said screw-holes between lugs 5 and 6, and screw-stop 8 can be engaged by a screw-driver through said slot or opening and 65 transferred from one opening to the other when desired. We prefer to use also a thin circular band or ring E, which rests snugly around the sides of said cap to close opening d' against the admission of dirt, and this band 70 or ring of course requires removal before changing the screw-stop.

75 This stop and waste cock is especially well adapted for high-pressure service, as the cap and flange on the plug engage the cap to securely hold the plug to its seat. The plug is heaviest at its upper end, and the cap engages the body and the plug where it is best adapted to stand the greatest strain.

80 The stop and waste cock thus described is more cheaply constructed, more durable, and the parts more readily released and removed when necessary without damage to any of the parts than the old-style cocks. This is of special value in cocks that have been in use 85 and require attention, especially after long service, and when the plug has become fixed in its seat it is practically impossible to rotate it without releasing the plug in some way. Our screw-cap serves not only to hold the 90 plug in its place, but provides for adjustment and release as well and also serves to act as a sand-cap and as a protecting inclosing casing for the stop members.

95 The lower end of plug B exposes a broad 100

flat surface at the bottom of the cock and provides a safe and convenient means for tapping by hammer or other instrument to drive the plug free from its seat if set and otherwise 5 difficult of removal.

What we claim is—

In a stop and waste cock, a body having a central water-passage and a waste-passage at one side, a screw-threaded extension upon 10 said body and a tapered valve-seat through said body, a tapering plug-valve in said seat provided with a water-passage and an annular shoulder at the top of said plug, a set of stops on said body and said plug beneath

15 said shoulder, a screw-cap to engage the threaded extension of said plug and said shoulder adapted to hold said plug to its seat and providing a chamber for inclosing said stops, an opening at one side of said cap, and a member for sealing said opening. 20

In testimony whereof we sign this specification in the presence of two witnesses.

CHARLEY S. MOOK.
BERNARD H. JANSEN.
